UNITED STATES PATENT OFFICE.

GEORGE A. PINGREE AND RICHARD A. UHLIN, OF SEATTLE, WASHINGTON.

AIR-TUBE AND DIRT-TRAP FOR OIL-BURNERS.

1,210,980.

Specification of Letters Patent.

Patented Jan. 2, 1917.

Application filed September 26, 1916. Serial No. 122,261.

To all whom it may concern:

Be it known that we, GEORGE A. PINGREE and RICHARD A. UHLIN, both citizens of the United States, residing at Seattle, in the county of King and State of Washington, have invented certain new and useful Improvements in Air-Tubes and Dirt-Traps for Oil-Burners, of which the following is a specification.

10 This invention relates to oil burners, and its object is to provide means for preventing back-firing, means for entrapping any particles of foreign matter that may be in the oil and for readily removing such matter from the communicating pipes.

15 To this end our invention consists in the construction and combination of parts forming an air tube and dirt trap for oil burners hereinafter more fully described reference being had to the accompanying drawing in which;

20 Figure 1 represents a longitudinal, vertical section partly in side elevation, of an air tube and dirt trap for oil burners according to our invention. Fig. 2 represents a top end view of the spraying tip with the nozzle removed.

25 Numeral 3 represents the oil vapor pipe, which, in burners of this order, have a portion of their length exposed to heat from the burner to serve as a retort for generating vapor or gas from the oil. The body 4 of this tip is provided with a nozzle 5 having a spraying outlet 6. A plunger 7 having a needle end 8 is fitted to reciprocate longitudinally in the tip to push any clogging matter out at 6.

30 The body 10 of the wire lever 9 passes through a cap nut 11 and screw 12 and the side of the tip and has a crank 13 on its head 14, that engages the plunger 7 to reciprocate it by revolutions of the said lever 9. The intake tube 15 is open to admit air at both ends, and is removably attached 35 to the tip 4 by fitting closely around the cylindrical projection 16 and resting upon the shoulder 17. The tube 18 being—in part—the subject of another application of even date herewith, Serial No. 122,262, is not now further described. Through it the oil vapor passes with air into a mixing chamber, of which adjacent portions are shown at 19.

35 The oil vapor pipe 3 enters the tip 4 at a point below the plunger 7 and opposite the blank wall 20 of the tip in order that

the current of incoming oil vapor may be suddenly stopped by the wall, to permit any detritus in the oil to fall to the bottom 21. To further intercept the passage 40 of dirt we locate a screen 22, of some material like wire netting of about 100 mesh, across the vapor passage.

45 The lower end 23 of the tubular tip 4 is conically chamfered both externally and internally to fit into a correspondingly chamfered annular seat in the base cap 24. This is to prevent the open end of the tip being spread or compressed out of true form by undue strain on the nut 24; it 50 being necessary to remove and replace this nut for cleaning purposes, by unskilled operatives. The chamber 25 outlined by the bore in the tip 4, the floor 21 and screen 22, forms a trap to catch any detritus carried in the oil vapor. In course of time, with the best of oil, and more frequently with common oil, the screen 22 becomes filled and coated, stopping the burner. This demands removal of the screen and 55 insertion of a new one, and to do this with little work and delay, we make the screens to fit closely into the tube 4, take off the nut 24, crowd the screen up to its place and replace the nut. The outlet 6, also, may 60 become clogged by an interior coating, so we make the nozzle 5, to be readily unscrewed by pliers inserted in either end of the intake tube 15, still leaving that tube 65 removably held upon the smooth projection 16 and shoulder 17. From this trap the vapor passes up beside the plunger 7 in grooves indicated by dotted line 26, to the outlet 6. The double conical seat of the tip 4 in the cap 24 permits that cap 65 to form a tight joint with little pressure, and to be easily removed to empty out whatever the trap may have gathered. The cylindrical fit of the intake tube 15 around the top of the tip 4, and the shoulder 17 70 supporting it steadily in place, prevents escape of gas around the tip that would otherwise be ignited in the fire-box of a stove where the burner is in service, and cause back fire. The steady inflow of air 75 at the ends of tube 15 prevents gas escaping there. This device tends to convenience and economy in the use of oil burners.

80 The simple arrangement of parts in this oil burner, so they may be easily removed for cleaning, repairs or adjustment is very important.

We claim;

1. In an air tube and dirt trap for oil burners, a tip connected with a retort, and having a spraying nozzle, and shaped 5 around the nozzle as a smooth cylinder with a shoulder; an air tube having an intake opening at each end, a delivery opening at one side and opposite thereto a cylindrical aperture fitted to the said smooth 10 cylinder and shoulder, whereby the air tube may be freely raised from the shouldered cylinder for removal.

2. An air tube and dirt trap for oil burners, comprising a spraying tip having 15 a trap chamber, a pipe for communicating with a retort and entering a side of the chamber; a screen fitted to securely engage the chamber wall by being pushed upward against a shoulder thereof; and a remov-

able lower end whereby a screen may be 20 inserted or removed.

3. An air tube and dirt trap for oil burners, comprising a tip, a pipe communicating with a retort, an air intake tube fitted at one side upon the said tip and 25 having a spraying nozzle removably secured to the tip and located within the intake tube; the latter having open ends whereby the nozzle is accessible for removal or replacing.

In testimony whereof we affix our signatures in presence of two witnesses.

GEORGE A. PINGREE.
RICHARD A. UHLIN.
